(57) **CLAIM**

The ornamental design for a sleeve for holding multiple digital video discs and graphics, as shown and described.

DESCRIPTION

FIG. 1 is a front perspective view of a sleeve for holding multiple digital video discs and graphics showing my new design;

FIG. 2 is a top plan view of the invention illustrated in FIG. 1;

FIG. 3 is a left elevation view of the invention illustrated in FIG. 1;

FIG. 4 is a front elevation view of the invention illustrated in FIG. 1;

FIG. 5 is a rear perspective view of the invention illustrated in FIG. 1;

FIG. 6 is a rear elevation view of the invention illustrated in FIG. 1;

FIG. 7 is a right elevation view of the invention illustrated in FIG. 1;

FIG. 8 is a bottom plan view of the invention illustrated in FIG. 1;

FIG. 9 is a rear elevation view of an alternative embodiment of the invention illustrated in FIG. 1; and,

FIG. 10 is a front elevation view of the embodiment shown in FIG. 9.

The broken lines shown throughout the figures, are understood to represent seams.
